UNITED STATES PATENT OFFICE.

WILLIAM J. DONIGAN, OF AMSTERDAM, NEW YORK, ASSIGNOR OF TWO-
THIRDS TO JOHN K. STEWART AND GEORGE A. CLARK, OF SAME PLACE.

CARDING APPARATUS.

SPECIFICATION forming part of Letters Patent No. 617,481, dated January 10, 1899.

Application filed September 30, 1898. Serial No. 692,283. (No model.)

To all whom it may concern:

Be it known that I, WILLIAM J. DONIGAN, of Amsterdam, in the county of Montgomery, in the State of New York, have invented new and useful Improvements in Carding Apparatus, of which the following, taken in connection with the accompanying drawings, is a full, clear, and exact description.

My invention relates to certain improvements in carding apparatus; and the object is to provide simple and effective means to support the web or sliver while it is being combed from the doffer-roll and moved to one side and to assist in such movement. Heretofore various devices have been used to support and to prevent the sliver from dropping down, such as boards covered with tin, also tin cylinders revolving under the sliver, and other supports which were mounted on the floor beneath the sliver to give it some support, but these being stationary cause a drag on the sliver after it is combed down from the doffer-card, while with my invention the sliver is supported and moved along easily without injury to the same.

To this end my invention consists in the combination of the doffer-roll, the rocking bar, and the doffer-comb carried and operated thereby with a plurality of fingers extending from the rocking bar and projecting below the comb in close proximity to the doffer-card.

In the drawings hereto annexed and forming a part of this specification, Figure 1 is a top plan view of the rocking bar, comb, and fingers. Fig. 2 is a vertical sectional view of the same, taken on line xx of Fig. 1; and Fig. 3 is a front side elevation of the devices and shows the sliver supported on the fingers while it is carried to one side preparatory to being twisted slightly, as usual, and wound upon a spool.

Referring specifically to the drawings, A is the rocking bar, and B is the cam-box containing the cam and other mechanism for rocking or oscillating the bar in the usual and well-known manner. Any suitable and well-known means for rocking the bar A may be employed, and as these are well known and form no part of my invention it will not

be necessary to show in detail or describe specifically the same.

B' is a double pulley on the cam-box shaft to be driven by a belt from some other revolving shaft in the machine. The said rocking shaft extends parallel with the doffer-roll and lies substantially in a horizontal plane extending through the shaft of the doffer-roll C. (Shown partially in Fig. 2 of the drawings.)

D is the doffer comb or blade, of the usual form, provided with teeth on its lower edge to engage the card on the doffer-roll C and comb therefrom the fibers collected thereon to form the sliver. The said comb is parallel with the rocking shaft A and is secured thereto by a series of rods E, arranged parallel side by side and extending through both the rocking bar and comb. The ends of the rods are riveted or otherwise secured in the bar and comb-blade. Extending downwardly through the rocking shaft and then forwardly toward the doffer-roll, so that their ends come in close proximity to the card thereon, are a series of fingers F, which move with the rocking bar and comb, and being below the comb serve to support the fibers when combed from the doffer-card. These fibers form what is known as the "sliver," which is drawn to one side and passed through rolls, and a revolving tube (not shown) which twists the same before it is wound on a spool.

The sliver G is indicated in both Figs. 2 and 3 as supported on these fingers F. As the comb is rapidly oscillated or raised and lowered in its operation, the fingers being also secured to the rocking bar are also rapidly raised and lowered, thus assisting in moving the sliver while supporting it, or at least in supporting it in such a manner that it is moved easily by other means and not injured or broken during such movement. The fingers are shown in an angular shape and with their free end portions lying parallel or nearly parallel with the rods E above; but I do not desire to be limited to the precise form of the fingers shown in the drawings, nor to their junction with the rocking bar, for these may be varied without departing from my invention. The fingers are shown

with their ends riveted in the bar; but they may be secured rigidly or adjustably therein in any suitable and well-known manner.

The broken lines in Fig. 2 indicate the different positions and range of movement of the rocking bar, comb, and fingers.

Having described my invention, what I claim as new, and desire to secure by Letters Patent, is—

- 10 1. In a carding apparatus, the combination of the doffer-roll, the rocking bar and the doffer-comb carried and operated by the rocking bar, with a plurality of fingers extending from the rocking bar, and projecting below the comb in close proximity to the doffer-card, substantially as described and shown.
- 15 2. In a carding apparatus, the combination of the doffer-roll, the rocking bar and the doffer-comb carried and operated by the rocking bar, with a plurality of fingers connected to and operated by the rocking bar, said fin-

gers extending in close proximity to the card on the doffer-roll, and with their free ends lying below the said comb and in substantially the same plane, as and for the purpose 25 described.

3. The combination of the doffer-comb, the rocking comb-shaft, a plurality of rods connecting the comb with its shaft, and bent fingers secured at one of their ends to the rocking bar, and having their free ends lying in a plane below the plane of the plurality of rods, and extending below the teeth of the comb, and adapted to be moved simultaneously with the comb, as and for the purpose 30 35 described.

In testimony whereof I have hereunto signed my name.

WILLIAM J. DONIGAN. [L. S.]
